UNITED STATES PATENT OFFICE.

JAMES W. HUGHES, OF HADDON HEIGHTS, NEW JERSEY, ASSIGNOR TO HUGHES-LIPPINCOTT COMPANY, A CORPORATION OF NEW JERSEY.

COIN-CONTROLLING REGISTER.

1,336,628.

Specification of Letters Patent. Patented Apr. 13, 1920.

Application filed June 1, 1915. Serial No. 31,629.

To all whom it may concern:

Be it known that I, JAMES W. HUGHES, a citizen of the United States, and resident of Haddon Heights, county of Camden, and 5 State of New Jersey, have invented an Improvement in Coin-Controlling Registers, of which the following is a specification.

This invention relates to a coin apparatus for operating automatic vending machines, 10 and has for an object to provide a means whereby a customer may order the various things he may desire by simply pressing the various keys on a keyboard labeled with the names of different articles. When the 15 various keys are pressed corresponding signals will be shown in a kitchen or store-room wherein the goods to be sold are prepared for dispensation. It has for a further object to provide a means to receive, to add, 20 and to register coins of various denominations, and when there has been placed into the machine a sum total of money equal or equivalent to the amount of the bill ordered on keyboard of the machine, either a check 25 will be ejected (from the apparatus) which may be used to operate and open a vending machine placed near by when the order appears in same, or else it can be directly connected to the vending machine itself and operate same instead of ejecting check as aforesaid. It has for a further object to provide 30 a means for operating an automatic vending machine set for a given sum of money, with any number of coins that will make up the 35 total amount regardless of the denominations of the coins used so long as the right amount be placed in the machine. For illustration suppose it is desired to sell an article for fifty cents. It is one of the objects of 40 my invention to provide a means whereby it will not matter whether ten nickels are placed in the slot or whether five dimes are used, or whether it consists of two quarters of a dollar, or one quarter and five nickels, 45 or any other combination of legal coins, when the right amount equivalent to the aforesaid fifty cents is placed in the slot the apparatus will either eject a check or operate a vending machine as desired.

50 With the above and other objects in view as hereinafter described, the invention consists in a novel construction of a keyboard wherein only one key at a time can be used, each causing a registration of the amount 55 thus ordered to be made and added up, and a

novel construction of an apparatus which will register the amount of and add up all coins placed therein, and when the sum total of the money received by the machine is equivalent to the sum total ordered on keyboard or otherwise set as desired, the machine will cause to operate a novelly constructed apparatus for discharging a check or delivering the goods.

Referring to the drawings: 65

Figure 1 represents an assembled elevation of the machine; Fig. 1^a is an end view of the machine of Fig. 1 with part in section; Fig. 2 represents a sectional plan view of the same; Fig. 2^a is an end view of the 70 same partly in section; Fig. 3 is an enlarged view of a typical key used on the keyboard showing the key in normal position ready to be pressed in; Fig. 4 is a similar view to Fig. 3 showing the key being pressed in; Fig. 5 75 is a similar view to Fig. 4 and showing the key all the way pressed in; Fig. 6 represents an enlarged section of the coin tube; Fig. 6^a is a cross section of the coin tube; Fig. 7 shows an enlarged elevation view of 80 the dial registering mechanism; Fig. 7^a is a side elevation of the registering mechanism with a portion broken away; Fig. 8 shows a detail of the locking key in locking position; Fig. 9 represents a sectional plan view 85 of a type of vending machine which may be used in connection with my coin controlled operating device; Fig. 9^a is a vertical section of the same; and Fig. 10 is an enlarged elevation showing the mesh plate and 90 differential plate with some of the keys omitted and others in section.

1 and 2 designate two mesh plates carrying a number of keys of which 3 is a type shown in the enlarged details Fig. 3, Fig. 95 4, and Fig. 5. 4 designates a sliding plate through which all of the order keys pass. The plate 4 I have termed a differential mesh plate because the pitch or position of the holes in this plate differs from the 100 pitch or position of the holes in plates 1 and 2 by a small increment or differential, so that no two of the plural holes in the plate 4 can be made to exactly coincide with any two of the plural holes in plates 1 and 105 2 at the same time. It is this principle that prevents more than one key from being pressed down at the same instant for the following reason: It will be noted that the key 3 is made smaller at the two points A 110

and B, and when either one of the smaller portions is in alinement with the differential plate 4 this plate can be shifted in any direction equal to the difference of the 5 diameter of the hole in plate 4 and the diameter of the smaller portion of key 3. Now as the larger portion of key 3 between the points A and B is a neat fit in the holes of plate 4 it follows it would be impossible 10 to push in two keys at the same time inasmuch as no two sets of holes as aforesaid can be made to exactly coincide. Now since from the nature of the construction any two holes in plate 4 can be made, one to coincide 15 and the other to partly eclipse any two corresponding holes in plates 1 and 2, it logically follows that any key on the board may be pushed in or out when taken one at a time, for whether the keys occupy the position 20 as shown in Fig. 3 or the position as shown in Fig. 5, it is clear to be seen that any single key when pressed will (due to the bevel of the reduced portions A and B) draw the hole through which it passes into 25 alinement with itself as the plate is free to move in any direction equal to the difference of the diameters of the holes and the reduced sections of the keys as heretofore explained.

From the foregoing it is clear to be seen 30 how no two keys can be operated at the same time—an important feature as hereinafter brought out. This being accomplished we will now proceed to demonstrate the method of registering the amount ordered and how 35 orders are made.

Referring to Fig. 1. This figure shows a keyboard carrying thirty-five keys of the type 3 as heretofore referred to. The fronts of the keys are labeled with the various 40 articles to be sold as indicated. The first two rows (reading from the top) are for five cent articles as indicated by the numerals to the left of each row. The third row is for ten cent articles, and the fourth, 45 fifth, sixth, and seventh rows are for fifteen, twenty, twenty-five, and thirty cent articles respectively as also indicated. On the underneath sides of the keys of type 3 are cut small gear racks with a number of teeth 50 corresponding in proportion to the number of nickels to be registered, with a clearance gap at either end of the rack space. The rack teeth on the keys 3, as shown, mesh (when pushed in) with the pinions indicated 55 by the number 5. Now the mechanism is so geared and arranged that when the key 3 in the five cent row is pushed in, the one tooth there shown will revolve the pinion 5 through two teeth which turns the indicator dial 6 through a space adding five cents. (The one tooth in the key 3 will 60 revolve the pinion 5 through a space of two teeth because of the space it has to pass before the tooth in 3 disengages and clears 65 the teeth in pinion 5.) 3' in the ten cent

row has three teeth, or two more teeth in it than has key 3 of the five cent rows, hence it will revolve the pinion 5' through a space of four teeth or ten cents as indicated on the registering dial. The fifteen to thirty 70 cent keys are geared to the registering dial at a ratio twice as great as the five and ten cent rows of keys, hence it will be clear to see how only half the number of teeth on each key will be required as if geared at the ratio of the smaller denomination of 75 keys. As shown in the drawings all of the pinions 5 are geared together by means of a steel wire or band as designated by the numeral 7 though they might be geared together by any other known methods such as spur idler gears as indicated by dot and dash 8, or by the use of ordinary bevel gears or spiral gears, or by chain and sprockets running in the place of steel wire 7. The 80 steel wire 7 takes several turns around the drums 9 and 10 to avoid any slip, and as the drums 9 and 10 only revolve in one direction a given number of times and then back again the steel music wire 7 may be 85 soldered at a single spot on said drums or otherwise permanently secured to make the movement of all pinions absolutely positive. I have resorted to the use of the aforesaid 90 music wire as a means of gearing the pinions 5, 5', and 5'' together in order to get an easily operated mechanism with the least amount of back-lash. The pinion 5' is 95 geared at the end to the dial gear 11 through the idler gear 12 which is positively connected to the indicating dial 6 which revolves on pin 13. In the bearing 14, the center line of which is concentric with the center line of 13, is mounted a hollow shaft 15 carrying secured thereto another dial 100 16 similar in construction and size to the dial 6. Secured to the dial 16 is the ratchet wheel 17 which is driven by the escapement like ratchet 18, which in its turn is operated by the armature 19 pulled by the electromagnet 20 when same is energized. Now 105 the magnet 20 is energized and nullified, causing repeated pulls on the armature, according to the value of the coin deposited, 110 as follows: In the tube 21 is secured two 115 pieces of insulating material 22 and 23 to form a slot or runway as shown in the enlarged section Fig. 6. In member 22 is inserted the metal strips 24, 25, 26, 27, and 28 as shown. The metal strip 24 acts as a bottom path or runway for the various size coins. Strip 25 is located at a distance from 24 approximately equal to the diameter of a ten cent coin and in this strip is one interruption electrically obtained by cutting 125 the gap 29 and filling same with an insulating material. Now when a dime is placed in the slot 30 it rolls down the runway 24 and when its upper edge reaches the member 25, it contacts and closes an electric circuit 130

passing from the battery 31 into the member 24, through the dime into the member 25, from hence through the magnet 20 returning to and through the battery 31, thus energizing the magnet 20 which pulls down the armature 19, which operates the ratchet 18 and drives the ratchet wheel 17 and dial through a space of one half of a tooth as armature descends. As the dime rolls on and passes on to the insulating gap 29 the circuit as described above is broken and the armature 19 springs back through the effort of the spring 32 and drives the ratchet wheel through a space of another half tooth, thus moving the ratchet wheel 17 through a space of one whole tooth at each make and break of the circuit. As the dime rolls farther on it again comes in contact with the metal of strip 25 after passing the gap 29, and the above operation is repeated driving the ratchet wheel through another tooth. Now as there is the same number of graduations of five cents each on dial 16 as there are teeth in wheel 17, it follows that every time the circuit is made and broken the registering dial will be five cents; and since strip 25 causes the circuit to be made and broken twice by the dime rolling over same, it is clear to be seen that the dial will be driven forward two spaces of five cents each, or a total of ten cents. The strip 26 is placed at a distance from strip 24 approximately equal to the diameter of a five cent coin, and as this strip has no interruptions in it, the circuit leading to the magnet 20 will only be made and broken once, thereby advancing the dial through only five cents as it should. The strip 27 is placed at a distance from 24 equal approximately to the diameter of a quarter of a dollar and contains four gaps of insulation which give five points of contact along its course thus making and breaking the circuit five times when a twenty-five cent piece rolls along its course. The strip 28 is a proper distance from 24 to engage the upper edge of a fifty cent coin when inserted, and contains nine gaps and ten points of contact which, by the same principle as before described, will advance the dial 16 through ten spaces of five cents each or cause to be registered fifty cents.

Referring to Figs. 7 and 7^a, an enlarged detail of part of the dials 6 and 16, it will be noted that through the hollow shaft 15 runs two conductors 33 and 34 terminating and connecting to the contact points 35 and 36. On the dial 6 is the split brush 37 so arranged that when it is opposite to the points 35 and 36, it will close a circuit as shown, which circuit passes through the solenoid 38 pulling on the key 39 to the position as shown in Fig. 8. The key 39, being similar in shape and size to the keys 3 and 3', when pulled by the action of the solenoid 38 will lock up the differential plate 4 and prevent

any keys on the board from being pressed until the order has been filled and the key 39 is set back to its normal position by the person in charge pressing on the button 40 of key 39. When the key 39 is drawn backward by the action of the solenoid 38, the lever 41, which is pivoted at 42, having one end working in a slot of key 39, the other end working under the bottom of the check magazine 43, will sweep out a check (to the customer) to be used for operating a vending machine when the goods ordered are prepared and shown ready for delivery. Now it is clear to be seen that, if the circuit which passes through the solenoid 38 is passed also through the magnet 44 of Fig. 9, the armature 45 will be pulled downward from off of pin 46 releasing turret 47 which will be revolved around through a space of about 180 degrees, thus giving access to the contents of the machine directly as is desired in case of ready prepared food, etc.

The operation of the machine may now be described briefly as follows:

When a customer wishes to order and procure (say for illustration) a meal in a restaurant equipped with this device, he presses the keys labeled with the articles he desires. This operation will drive the dial 6, as described above, registering the amount of purchase, and carrying the brush 37 around correspondingly. At the same time the key is pressed it will show as pushed out or raised on the opposite side of the machine or in the serving room, thereby notifying the one in charge of the special order desired. If for instance the total bill thus ordered comes to fifty cents, then the customer starts to place in whatever coins he may have at his command until the dial 16 is driven around to a corresponding position of fifty cents, when the two contact points will come in contact with the circuit closing brush 37 which closes the circuit 48 on the solenoid 38 ejecting the check 49, which may be used as a means for opening the automatic vending device as shown in Fig. 9, while at the same time the coins run through the elbow 50 and slide down between the glass 51 and the plate 52 bringing the coins in view of the customer as well as visible to the one serving on the opposite side of the machine. When the coins are inspected by the one in charge the plate 52 is pulled outwardly, thus allowing the coins to supports to fall into the money drawer 53. 54 designates a ratchet counter which is geared to the dial 16 and registers the total amount of money received.

I wish it to be further understood that the keyboard in many cases will not be used where single ready prepared articles are to be sold. In which case the keyboard causing carrying the keys 3 and 3' will be eliminated and the dial 6 will be set at a figure

corresponding to the price for which the article is to be sold, and the circuit 48 will be made to pass through a magnet for unlocking a vending machine containing the 5 merchandise to be sold. Then when a sufficient amount of coin has been placed in the machine to cause the dial 16 to correspond to dial 17 the circuit thus established in 48 will unlock and deliver the goods de- 10 sired.

The present application is limited to the invention involving the keys and plates, whereby only one key may be moved at a time, associated with means for registering 15 the amount ordered by the operation of the keys, the remaining parts being parts of the mechanism shown forming subject matter of my application Serial Number 198,028, and filed Oct. 23, 1917.

20 Having thus described my invention, what I claim as new and desire to protect by Letters Patent is:

1. In a device of the character stated, an order board having two faces, in combination 25 with a plurality of keys indicating the various articles for sale and extending through the board and beyond its two faces so as to be operable from either face, means for registering when the keys are operated 30 from one face only of the board and without registering when operated from the other face of the board, and devices for permitting only one key to be operated at any one time.

35 2. In a device of the character stated, a frame having a fixed plate, a movable mesh plate parallel thereto and movable longitudinally and transversely to the plane of its surface, a plurality of reciprocable reg- 40 istering keys each having a large and a small portion guided in the fixed plate and extending through the movable mesh plate to shift it, the holes of said plates for the keys relatively spaced at a differential pitch 45 to prevent more than one key from being operated at the same time, means operated by the keys to register the operation thereof, a master locking key for locking the movable mesh plate against action by the regis- 50 tering keys, means to control the time of action of the master locking key, and manually controlled means for causing the locking key to be moved out of locking position when desired.

55 3. In a device of the character stated, a frame work, combined with a plurality of

keys arranged in a plurality of rows each key having a beveled shoulder and also a portion reduced in cross section adjacent to the shoulders, said keys arranged parallel 60 in the frame work, a movable differential backing plate through which the keys work said plate having holes spaced differently from the spacing of the keys both as to the spacing in each row and as to the spacing 65 of the plurality of rows, the edges of the said holes co-operating with the beveled shoulders and reduced portions of the keys and whereby the plate is movable by any key when operated alone, and suitable means 70 independent of the keys to hold the plate against movement by the keys.

4. In a device of the character stated, the combination of an order board, a plurality of keys designating the various articles 75 for sale said keys supported in parallel rows on the board, an indicating dial for registering the amount ordered by the operation of any portion of the keys, and means comprising a plate through which all of the 80 keys pass and movable under the action of the keys in different angular directions in the plane of its surface for preventing more than one key of the plurality of rows of keys being positively operated at one time. 85

5. In a device of the character stated, an indicating dial, and a plurality of keys arranged in a series of parallel rows and geared to operate the indicating dial, combined with a movable differential plate com- 90 mon to all of the keys and movable in all directions in the plane of its surface to prevent the operation of more than one key at a time, said plate movable by any single key 95 of any row at one time.

6. In a device of the character stated, a plurality of keys each of which has rack like edges of relatively different numbers of teeth, an indicator dial, a series of pinions in geared relation so as to rotate together and operate an indicating dial, said pinions actuated by the keys in proportion to the amount of registering it represents, and means movable longitudinally and transversely of the same plane to prevent 105 the operation of more than one key at a time.
